No. 746,364.

PATENTED DEC. 8, 1903.

J. A. MCKENZIE,
GAME APPARATUS.

APPLICATION FILED SEPT. 1, 1903.

NO MODEL.

Fig. 1.

UNITED STATES PATENT OFFICE.

JOSEPH A. MCKENZIE, OF BROOKLYN, NEW YORK.

GAME APPARATUS.

SPECIFICATION forming part of Letters Patent No. 746,364, dated December 8, 1903.

Application filed September 1, 1903. Serial No. 171,494. (No model.)

To all whom it may concern:

Be it known that I, JOSEPH A. MCKENZIE, a citizen of the United States, residing at Brooklyn, in the county of Kings and State of New York, have invented certain new and useful Improvements in Game Apparatus, of which the following is a specification, such as will enable those skilled in the art to which it appertains to make and use the same.

This invention relates to game apparatus; and the object thereof is to provide improved means for setting or spotting the pins in a game of tenpins, whereby the pins may be quickly and exactly placed, a further object being to provide means or devices for accomplishing this object which may be applied either to an ordinary tenpin-alley or to tenpin-alley tables or similar devices by means of which a game of tenpins may be played in a parlor, café, saloon, or other places where game apparatus of this class are usually to be found.

The invention is fully disclosed in the following specification, of which the accompanying drawings form a part, in which the separate parts of my improvement are designated by suitable reference characters in each of the views, and in which—

Figure 1 is a sectional end view of the rear end of a tenpin-alley provided with my improvement; Fig. 2, a section on the line 2 2 of Fig. 3; Fig. 3, a sectional plan view, part of the ballway being broken away; and Fig. 4, a section on the line 4 4 of Fig. 3.

In the drawings forming part of this specification I have shown at *a* the ballway of a tenpin-alley, at the opposite sides of which are the gutters *a*² and at the rear end of which is the ordinary pit *a*³, part of which is shown in Fig. 3. At the opposite sides of the alley and inclosing the sides of the pit are the usual upright buffers *a*⁴, and all these parts may be of the usual or any preferred construction.

In the practice of my invention I form beneath the pin-space at the rear end of the ballway a chamber *c*, having a bottom *c*², in which, in the form of construction shown, are secured upright posts *d*, which equal in number the pins *e* and are placed directly beneath the position occupied by said pins when properly positioned on the ballway or pin-space at the rear end thereof. The ballway

or that part thereof known as the "pin-space" is provided with a plurality of circular openings *f*, which equal in number the pins employed and which are formed at the exact points where in practice the pins are spotted or placed.

Beneath the pin-space of the ballway and transversely of the chamber *c* and near the front wall *c*³ of said chamber is a shaft *g*, mounted in bearings *g*² and provided near its opposite ends with cam-arms *g*³, and forwardly of the shaft *g* is another transverse shaft *h*, mounted in bearings *h*² and provided with cam-arms *h*³.

Directly over the shafts *g* and *h* and within the top portion of the chamber *c* is placed a vertically-movable plate, frame, or support *i*, with the top of which is connected in any desired manner cylindrical plugs *i*², which equal in number the pins *e* and the holes or openings *f* in the pin-space of the ballway and which are free to move vertically in said holes or openings. The posts *d* pass vertically through the support *i* and serve as a guide therefor, and said posts also pass vertically through the plugs *i*², and the pins *e* are preferably provided in the bottoms thereof with a recess *e*², and in the form of construction shown the upper ends of the posts *d* when the support *i* is in its lowest position projects slightly above the plugs *i*² and are adapted to enter the recesses *e*² in the bottom of the pins *e* when the latter are placed in position.

In the form of construction shown the gutter *a*² at one side of the alley is provided with a longitudinal slot *a*⁵, and secured to the end of the shaft *g* is a lever *j*, which passes upwardly through said slot *a*⁵, and secured to the corresponding end of the shaft *h* is a crank *k*, which is connected, by means of a rod *k*², with an arm *j*² on the lever *j*.

The rear end portion of the plate, frame, or support *i* is provided at its opposite sides with projecting bearings *m*, and the front end portion thereof with corresponding bearings *m*², and when the lever *j* is pulled backwardly into the position shown in Fig. 2 the cam-arms *g*³ and *h*³ on the shafts *g* and *h* operate, in connection with the bearings *m* and *m*², to raise the plate, frame, or support *i*, and in this operation said plate, frame, or support is raised until it strikes the bottom of the ball-

way or the pin-space thereof, as shown in Fig. 2, and in this position of said support the tops of the plugs i^2 are exactly flush with the surface of the ballway a , as is also shown 5 in said figure.

In practice when it is desired to spot or place the pins e the lever j is swung into the position shown in Fig. 1. The pins e may then be quickly placed in position, as indicated in 10 said figure, in which the bottoms of said pins are set into the holes or openings f and rest on the plugs i^2 , and this operation may be quickly and easily accomplished without the exercise of the care necessary to properly place the 15 pins under ordinary circumstances. When the pins have been placed as indicated in Fig. 1, the lever j is drawn backwardly into the position shown in Fig. 3, and the pins are raised into the position shown in said figure, 20 and the plugs i^2 are exactly flush with the top surface of the pin-space.

The object of forming the recesses e^2 in the bottom of the pins e and correspondingly extending the upper ends of the posts d , so as 25 to enter said recesses when the parts are in the position shown in Fig. 1, is to aid in steady- 30 ing the pins when they are dropped into position; but this construction is not absolutely necessary, as the apparatus will work sub- 35 stantially in the manner herein described if the posts d are not long enough to project above the tops of the plugs i^2 when the latter are in their lowest position.

It will be observed that when the lever j is 35 in the position shown in Fig. 1 the plate, frame, or support i rests on the heads of the cam-arms g^3 and h^3 , through which the shafts g and h pass, and when the lever j is drawn backwardly into the position shown in Fig. 40 2 the said plate, frame, or support rests on the curved end portions of said arms, and, if necessary, means may be provided for holding the lever j against accidental movement when in the position shown in Fig. 2, and this 45 result can be accomplished, if necessary, by simply weighting said lever. It will be observed also that both the posts d and the plugs i^2 , in the form of construction shown, 50 serve to guide the plate or support i in its vertical movement; but my invention is not limited to the exact form, construction, and

combination and arrangement of the various parts thereof as herein shown and described, and various changes in and modifications of the same may be made without departing 55 from the spirit of my invention or sacrificing its advantages, and I reserve the right to make all such alterations therein as fairly come within the scope of the invention.

Having fully described my invention, what 60 I claim as new, and desire to secure by Letters Patent, is—

1. A game apparatus of the tenpin class, the pin-space of which is provided with holes or openings, a vertically - movable support 65 mounted beneath the pin-space and provided with plugs movable in said holes or openings, stationary guides which pass vertically through said support and through said plugs and means for raising and lowering said support consisting of shafts mounted transversely beneath the same and provided with cam-arms which operate in connection therewith and a lever connected with one of said shafts and in operative connection with the other, 70 substantially as shown and described.

2. A game apparatus of the tenpin class, the pin-space of which is provided with holes or openings, a vertically - movable support mounted beneath the pin-space and provided 80 with plugs movable in said holes or openings, stationary guides which pass vertically through said support and through said plugs and the upper ends of which project slightly above said plugs when said support is in its 85 lowest position, and means for raising and lowering said support consisting of shafts mounted transversely beneath the same and provided with cam-arms which operate in connection therewith, and a lever connected 90 with one of said shafts and in operative connection with the other, substantially as shown and described.

In testimony that I claim the foregoing as my invention I have signed my name, in presence of the subscribing witnesses, this 31st day of August, 1903.

JOSEPH A. MCKENZIE.
